UNITED STATES PATENT OFFICE.

HENRY LANGE, OF QUINCY, ILLINOIS.

COMBINATION COAL AND GAS HEATER.

1,315,518.

Specification of Letters Patent.

Patented Sept. 9, 1919.

Application filed March 31, 1919. Serial No. 286,293.

To all whom it may concern:

Be it known that I, HENRY LANGE, a citizen of the United States, residing at Quincy, in the county of Adams and State of Illinois, have invented certain new and useful Improvements in Combination Coal and Gas Heaters; and I do hereby declare the following to be a full, clear, and exact description of the invention, such as will enable others skilled in the art to which it appertains to make and use the same.

This invention relates to air heating stoves and furnaces, and more especially combination coal and gas heaters, it being the primary object of the invention to provide a stove which has in addition to the usual provision for the burning of coal or solid fuel, novel and improved means for burning gas or other hydrocarbon fuel, in order that both solid and fluid fuels can be used either jointly or severally as desired by the user.

One of the specific objects of the invention is the provision of a gas burner surrounding the fire pot and assembled with said fire pot and ash pit in a novel manner, with a simple and effective construction.

Another object is the assemblage with the burner and fire pot of an inclosing jacket for the burner to confine the products of combustion therein so as not to pass out into the room and to permit said products of combustion to circulate around the fire pot and then into the main combustion chamber of the heater, said jacket being assembled with the burner and ash pit in a manner to be removed for purpose of cleaning or repairs.

A further object is the provision of a grate or grid supported above the burner within the jacket in a novel manner for supporting refractory material to be heated by the gas flames so as to not only radiate heat to the walls of the jacket, but to also give the appearance of burning coal through the transparent panels or sides of the jacket.

A still further object is the provision of novel, yet simple and effective means for conducting the products of combustion from within the gas combustion chamber into the interior of the stove and thence upwardly to pass through the usual smoke outlet, and establishing the circulation of

the products of combustion from the gas burner, so as to give off the heat through the drum or shell of the stove, and to also prevent coal or other fuel dumped into the stove from passing down into the gas combustion chamber or clogging up the gas flues.

It is also the object of the invention to provide such a combination of coal and gas heater comprising a comparatively simple construction of the component elements and a simple and practical combination and assemblage thereof, in order that the parts can be readily assembled and taken apart, and providing for a thoroughly practical and serviceable structure.

With the foregoing and other objects in view which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a vertical section taken from the front to the rear, portions being shown in elevation.

Fig. 2 is a vertical section taken from side to side at right angles with the plane of section in Fig. 1.

Figs. 3, 4 and 5 are horizontal sections taken on the respective section lines 3—3, 4—4 and 5—5 of Fig. 2.

The stove or heater, for the purpose of burning coal or other fuel, is of about the usual construction, and includes the ash pit 1 on which is mounted the fire pot 2, with a suitable grate 3 at the bottom thereof, said fire pot comprising a ring or annular wall, the upper edge of which is provided with an outstanding flange or rim 4. The upstanding drum or shell 5 of the stove is supported by the fire pot 2, and is provided with a suitable fuel door 6, and a top 7 provided with the usual smoke outlet or collar 8 through which the products of combustion pass, this outlet or collar 8 being usually at the rear and the door 6 at the front of the stove. The stove so far described is of conventional form for burning solid fuel in the usual way.

In order that gas or other fluid hydrocar-

bon can be burnt, there is provided an annular gas burner 9, comprising a hollow ring surrounding the fire pot 2 at the lower portion thereof immediately above the ash pit 1, and this burner is provided with an outstanding gas entrance 9a at the rear through which the gas is supplied to pass into the annular chamber of the burner and out through the apertures in the top. This 10 burner 9 is placed on the ash pit, and is supported thereby, and the fire pot is then seated on the ash pit within the burner, in assembling the parts. The burner 9 is provided at suitable points thereof with transverse ribs 10 extending along the bottom thereof and projecting upwardly slightly at the inner side of the burner, and said ribs seat on the ash pit to support the burner slightly thereabove, thereby permitting air 15 to flow under the burner over the ash pit, said burner being spaced from the wall of the fire pot, to permit the air to flow upwardly within the burner to the flames, so as to facilitate combustion of the gas. The 20 ribs 10 not only space the burner above the ash pit, but also space it from the wall of the fire pot, so that a desired amount of air can enter the gas combustion chamber from within the burner. The wall of the fire pot 2 has 25 lugs 11 that seat down on the ribs 10, in order that the burner will be held down securely in place on the ash pit 1, by the securing means 12 which fasten the fire pot 2 down on the top or shoulder of the ash pit 1.

30 35 A jacket 13 extends from the outer side of the burner 9 to the flange 4 of the fire pot, and provides an inclosed air combustion chamber above the burner surrounding the fire pot. This jacket 13 is preferably bulged outwardly or of swell formation, for purpose of ornate appearance, and is composed of front, rear and side sections each of which include outer and inner longitudinally and transversely curved frames 14 and 15, respectively, with transparent panels 16 clamped therebetween, and composed of mica or similar material. These frames 14 and 15 are provided with openings throughout exposing the panels 16 and not only permitting the heat to pass through but also permitting the flames to be seen through the sides of the walls of the jacket. Although the rear jacket section is shown of the same construction as the side and front sections, it 40 45 50 55 60 65 can be of a solid plate of metal, especially when the rear of the stove is not exposed to view. The ends of the jacket sections fit together and overlap, as seen in Fig. 3, and thus extend completely around the firepot in annular form. The lower edges of the jacket frames 14 are provided with downwardly extending lugs 17 that enter apertured ears 18 projecting outwardly from the outer side of the burner 9, the lower edges of the jacket sections being thus supported from the

burner 9, while their upper edges are secured to the flange or rim 4 of the fire pot. Thus, the upper edges of the frames 14 have lips 19 to bear against the edge of the flange 4, and said lips of the side and rear jacket 70 sections are secured to said flange 4 by means of bolts 20 or the like, while the front jacket section has its lip 19 removably clamped to the flange 4 by means of a manually operable catch 21. In applying the jacket sections, 75 the lugs 17 are inserted downwardly in the ears 18, thereby permitting said sections to be swung against the flange 4 and secured, and the catch 21 permits the front jacket section to be released and removed when access 80 is wanted into the gas combustion chamber. This jacket provides an annular combustion chamber above the burner 9 around the fire pot, which, can contain lumps of refractory material, so as to be heated red hot by the 85 flames, for not only giving heat, but to also give the appearance of burning coal.

When such refractory material is used, arcuate grates or grids 22 are disposed above the burner 9 within the jacket 13, and are 90 arranged end to end so as to extend completely around the fire pot over the burner 9. These grates or grids 22 will support the lumps or pieces of refractory material above the burner 9, and in order to support 95 said grates or grids above the burner, the outer edges of said grates have outstanding flanges 23 seated on lugs 24 projecting inwardly from the inner frames 15 of the jacket 13, while the grates 22 are provided 100 at their inner edges with downwardly extending lugs 25 seating on the burner 9. These grates or grids 22 can be readily inserted and removed, as they are simply seated on the jacket 13 and burner 9.

105 In order to conduct the products of combustion from within the gas burner into the stove, the wall of the fire pot 2 is provided at opposite sides and near its upper edge with series of openings 26, permitting the 110 gas to pass from the gas chamber within the jacket 13 inwardly through said openings. Thus, the products of combustion circulating within the gas chamber surrounding the fire pot can flow inwardly through the openings 26 to ultimately pass through the smoke outlet 8 of the stove, without a special outlet for the products of combustion from the burnt gas. In other words, the products of combustion from coal and gas both pass out through the usual smoke outlet 8, instead of there being separate outlets for coal and gas.

115 120 125 As a means for conducting the products of combustion from the openings 26, there is provided upon the interior of the fire pot 2 and drum or shell 5 of the stove means for that purpose, including a vertical flue 27 at the back of the stove, and horizontal flues 28 at the opposite sides. These flues 27 and 28 each consist of a metal plate, preferably 130

of cast metal, and the flue 27 is disposed vertically adjacent to the drum 5 parallel therewith and is curved transversely, as seen in Fig. 4, according to the curvature of the drum 5, while the flues 28 are curved longitudinally concentric with the drum 5, as seen in Fig. 3. The lower edges of the flues 27 and 28 have portions 29 seating on an annular seat or shoulder 30 with which the wall of the fire pot is provided on the interior thereof immediately below the horizontal plane of the openings 26. The side or vertical edges of the flue 27 are provided at the lower end of said flue with flanges 31 overlapping the rear ends of the flues 28 so that the rear ends of the side flues 28 communicate with the rear vertical flue 27, and this also holds the rear ends of the side flues in place against the rear of the drum 5 and fire pot. The flue 27 has its vertical side edges extending rearwardly, as at 33, and contacting with the drum 5, and said flue has side openings 34 at its lower end registering with the rear ends of the flues 28, and said flue 27 also has side openings 35 at its upper end discharging the products of combustion toward the opposite sides. The flue 27 is below the smoke outlet 8, so that the products of combustion in passing through the openings 35 will then pass upwardly through the smoke outlet, and these openings 35 are sufficiently high up so that coal or other fuel dumped into the stove will not fall down through said openings. The forward ends 35 of the flues 28 are curved toward and shaped, as at 32, to closely fit the fire pot and drum. The flue 27 has recessed portions 36 extending rearwardly and fastened by means of bolts 37 or the like to the back of the drum 5, thus clamping said flue thereto, and the flues 28 are provided with similar recessed portions 38 fastened by means of bolts 39 or the like to the drum 5 near the forward ends of said flues 28 and front wall of the drum. This secures the forward end of the flues 28 to the drum while the rear ends are held thereto by the flanges 31 of the flue 27. The upper edges of the flues 28 are curved toward and contact with the drum 5, as at 40, to retain the products of combustion in said flues and prevent coal or ashes falling down into said flue, and the upper end of the flue 27 is also curved toward and in contact with the back of the drum, as at 41. Thus, any coal, ashes or other particles falling on the flues will be shed downwardly into the fire pot.

When the gas burner is lighted, the products of combustion after circulating in the gas combustion chamber within the jacket 13 around the fire pot 2, will pass through the openings 26 into the flues 28 and will circulate rearwardly and pass upwardly within the flue 27 and out through the openings 35 to the smoke outlet 8. Thus, the

products of combustion from the gas burner will circulate from the gas combustion chamber into the stove, being confined within the flues 28 and 27 to pass along the wall of the drum 5, thus giving out additional heat 70 through said drum and ultimately permitting the products of combustion from the gas burner to pass off through the smoke outlet 8 provided in the usual manner for the burning of coal or solid fuel, so that no special outlet for gas is needed. The flues or shields 28 not only direct the products of combustion into the flue 27, but also prevent coal and other matter from falling down through the openings 26 into the gas combustion chamber, as would naturally be objectionable. Thus, the ventilating flues or outlet passages of the gas combustion chamber are located within the drum or shell of the stove, and the arrangement is such that 80 it will not interfere with the burning of coal. Such ventilating means is simple, embodying only the three plates or flues 27 and 28 which can be readily applied within the stove. The burner construction is also 85 equally simple on the exterior of the fire pot, and the entire construction provides for practical manufacture and use.

Having thus described the invention, what is claimed as new is:

1. A heater having an ash pit, a fire pot mounted thereon, and a burner surrounding the fire pot and mounted on the ash pit, said burner and fire pot having coöperating portions so that the fire pot holds the burner 100 down on the ash pit.
2. A heater having an ash pit, a fire pot mounted thereon, and a gas burner surrounding the fire pot, said burner having transverse ribs extending along its bottom and inner side seatable on the ash pit and engageable with the fire pot for spacing the burner therefrom to admit air at the inner side of the burner, the fire pot having portions bearing on said ribs to hold the burner 110 down on the ash pit.
3. A heater having an ash pit, a fire pot mounted thereon, and a gas burner surrounding the fire pot and having portions seating on the ash pit to space the burner therefrom for the admission of air at the inner side of the burner, the fire pot having portions to bear down on portions of the burner for holding it down on the ash pit.
4. A heater embodying an ash pit, a fire 120 pot mounted thereon, and a gas burner seated on the ash pit at the exterior of the fire pot, said fire pot having means to bear down on the burner and hold it on said ash pit.
5. A heater having a fire pot, a gas burner 125 surrounding same, and a jacket inclosing a gas combustion chamber having its lower edge supported by said burner to surround same.
6. A heater embodying a fire pot, a gas 130

- burner surrounding same, and a jacket inclosing a gas combustion chamber having its lower edge supported by said burner and its upper edge secured to the fire pot.
5. 7. A heater embodying a fire pot, a gas burner surrounding it, and a jacket inclosing a gas combustion chamber surrounding the fire pot, the lower edge of said jacket and outer side of the burner having portions 10 to interengage and support said jacket from the burner, the upper edge of the jacket and fire pot having portions clamped together.
8. A heater embodying a fire pot, a gas burner at the exterior thereof, a jacket inclosing a gas combustion chamber above the burner at the exterior of the fire pot, said fire pot having an opening in its wall leading from said chamber into the interior for the flow of the products of combustion from 20 said chamber into the heater to discharge through a common outlet, and means shielding said opening for preventing coal from falling therethrough from within the fire pot.
9. A heater embodying a fire pot, a gas burner at the exterior thereof, a jacket inclosing a gas combustion chamber above the burner, said fire pot having an opening in its wall leading to the interior from said chamber, and means on the interior of the 30 heater for conducting products of combustion from said opening, to a point of outlet higher up and shielding said opening to prevent coal from falling therethrough from within the fire pot.
35. 10. A heater embodying a fire pot, a gas burner at the exterior thereof, a jacket inclosing a gas combustion chamber above the burner, said fire pot being provided at opposite sides with openings leading to the interior from said chamber, and means at the interior of the fire pot for conducting the products of combustion from said openings rearwardly to a common point and then upwardly, and also shielding said openings to prevent coal from falling therethrough from within the fire pot.
50. 11. A heater embodying a fire pot, a drum above it, provided with a smoke outlet, a gas burner at the exterior of the fire pot, a jacket inclosing a gas combustion chamber above said burner at the exterior of the fire pot, and means for conducting the products of combustion from said chamber into and along the wall of the drum to a point 55 near said outlet to discharge therethrough and to serve as a shield to prevent coal from falling from within the fire pot and drum into said chamber.
60. 12. A heater embodying a fire pot, a drum above it, having a smoke outlet, a gas burner at the exterior of the fire pot, a jacket inclosing a gas combustion chamber above said burner at the exterior of the fire pot, said fire pot having an opening leading to the 65 interior from said chamber, and means at

the interior of the drum for conducting products of combustion from said opening along the wall of the drum at the inner side thereof to a point near said outlet to discharge therethrough and serving as a shield 70 to prevent coal from falling through said opening from within the fire pot.

13. A heater embodying a fire pot, a drum above it, a gas burner at the exterior of the fire pot, a jacket inclosing a gas combustion 75 chamber above said burner at the exterior of the fire pot, said fire pot having openings at opposite sides leading to the interior from said chamber, and means fitting the interior of the fire pot and drum for conducting the 80 products of combustion at the interior of the fire pot and drum from said openings rearwardly along the wall of the fire pot and drum and thence upwardly along the wall of the drum and shielding said openings to prevent coal from falling through said openings from within the fire pot into said chamber.

14. A heater embodying a fire pot, a drum above it, a gas burner at the exterior of the fire pot, a jacket inclosing the gas combustion chamber above said burner, the fire pot having an opening leading to the interior from said chamber, and a flue plate at the interior of the fire pot and drum having its edges fitting the walls thereof for conducting the products of combustion from said opening, and shielding said opening to prevent coal falling therethrough from within the fire pot into said chamber.

15. A heater embodying a fire pot, a drum 100 above it, a gas burner at the exterior of the fire pot, a jacket inclosing a gas combustion chamber above said burner, said fire pot having openings at opposite sides leading to the interior from said chamber, a vertical flue plate at a point between the sides having its edges fitting the wall of the drum, and side flue plates at the inner side of said openings and extending to the vertical flue plate for conducting the products of combustion from 105 said openings to the vertical flue plate.

16. A heater embodying a fire pot, a drum above it having an upper smoke outlet, a gas burner at the exterior of the fire pot, a jacket inclosing a gas combustion above said burner, the fire pot having openings at its opposite sides leading to the interior from said chamber, a vertical flue plate within the drum below said outlet and having its vertical edge portions and upper end fitting the wall of the drum, said flue plate having side openings at its lower and upper ends, and arcuate side flue plates having their adjacent ends fitting the lower portion of the vertical flue plate in communication with the 120 lower side openings thereof, the upper edges and other ends of said side flue plates fitting the drum and fire pot, the lower edges of said side flue plates and lower end of the vertical plate and fire pot wall having por- 125 130

tions fitting together below said openings so that the side flue plates conduct products of combustion from said openings rearwardly along the walls of the fire pot and 5 drum to the vertical flue plate which conducts them upwardly therein to the upper side outlets thereof.

In testimony whereof I have signed my name to this specification in the presence of two subscribing witnesses.

HENRY LANGE.
